UNITED STATES PATENT OFFICE.

WALTER BERESFORD, OF LIVERPOOL, ENGLAND, ASSIGNOR OF TWO-THIRDS
TO JOSEPH RICKARD CRELLIN, OF ILFORD, AND FREDERICK THOMAS
RUSHTON, OF LONDON, ENGLAND.

TYPE-WRITER.

SPECIFICATION forming part of Letters Patent No. 664,011, dated December 18, 1900.

Application filed March 10, 1900. Serial No. 8,178. (No model.)

To all whom it may concern:

Be it known that I, WALTER BERESFORD, a subject of the Queen of Great Britain and Ireland, and a resident of 118 Needham road, 5 Liverpool, county of Lancaster, England, have invented certain new and useful Improvements in Type-Writers, (for which I have made application in Great Britain, No. 16,437, dated August 12, 1899,) of which the following 10 is a specification.

This invention relates to type-writers, and has for its object to simplify the construction and produce a machine practically noiseless in use and one in which the writing-surface 15 is visible to the operator.

According to my invention I combine with the type-bars or rigid type-carrying parts of type-writers a hammer and a check-action and resilient check or checking mechanism 20 so combined and arranged that when the type-bars or other parts are operated the type are brought to or within a short distance of the printing-surface and then checked and impelled or struck upon the printing-surface by 25 a hammer operated by or through the impulse given to or momentum of the type-bars or key-levers, as the case may be. For instance, the hammer may be mounted on the same centering as the type-bar or on the rear of the 30 latter, so as to follow its movement, and then act upon the type-bar when checked to print, as described. Each set of type-carrying bars may be provided with a separate hammer, or one hammer may be common to all the type. 35 The said check-action is common to all the type-bars and is or may be adapted to be released by the hammer coming into contact with a lever or projection connected to the check, which lever or projection may be so 40 constructed as to form a fork through which the type-bars will pass, but not engage.

It is to be understood that I may without departing from the nature of my invention apply a check or check and hammer to type-writers of various construction and with various arrangements of keys or key-levers. 45

In further description I will refer to the accompanying drawings, in which—

Figure 1 is a plan of one form of my improvements in type-writers. Fig. 2 is a central longitudinal section on line 1 2 of Fig. 1. Fig. 3 is a front view with certain parts removed. Figs. 4 and 5 are side elevations showing, together with Fig. 2, the operation of a single type-bar and check-action. 50

In the arrangement shown the type-bars *a* and key-levers *b* are arranged to lie one above another when in normal position, as in Fig. 2, the former resting on a suitable support *c*. The type-bars *a* are suitably stamped or otherwise formed at their rear end with a circular aperture, bush, or ring *d*, (shown clearly in Figs. 2, 4, and 5,) adapted to fit and freely rotate upon a bearing *e* common to all the bars *a* or a number of same. Said bearing *e* 60 consists of a bar or spindle, which is or may be of somewhat large diameter, as shown, and is arranged in a curve correspondingly to the radial disposition of the type-bars *a* and levers *b*. As shown in the drawings, the bearing *e* is curved in both the horizontal and vertical planes, so as to better bring all the type to the common printing-center. The bush or ring *d* is provided with a stop or projection *m* for engaging the check-action, as hereinafter described. The key-levers *b* are centered in a comb *h* at their inner ends and adapted to operate the type-bar *a* through intermediate levers *b'*, centered at *b*². These levers *b'* are connected to the lever *b* by links *b*³, and 70 their inner ends are connected to and adapted to operate the type-bars *a* by a hinge-pin and slot or pivoted connections *f*, arranged, as shown, upon the bushes *d*, referred to. The said levers *b'* are curved where required, 75 as at *g*, to insure an easy motion when operated.

Fig. 2 shows the parts in a position of rest, the type-bars *a* resting on the support *c*.

The parts described are so adjusted that 80 in operation on full depression of a key-lever *b* by one of the keys *j* a type-bar *a* is brought at or within a short distance of the printing-center *k* on the front face of the printing-platen *l* and then temporarily stopped, as 85 shown in Fig. 4, by its stop *m* engaging the

check-action, hereinafter referred to, the printing action being then accomplished by means of a hammer *n*, mounted and hinged, as at *o*, upon the same bush *d* as the type-bars *a*, although the said hammers may be hinged to the back of the latter in suitable position, if desired. A suitable stop, such as *p*, is provided to prevent backward movement, so that the hammer *n* rises with and follows the movement of the type-bars *a*, and when the latter is checked, as described, the said hammer at once engages same (at the same time releasing the check) and impelling or striking the type-lever *a*, so as to carry the type thereon forward onto the printing-surface *l*. The check mechanism referred to comprises the lever *q*, disposed centrally of and projecting toward the group of type-bars, as shown, and hinged at its base to the machine-frame at *r*. This lever carries the check-bar *s*, which is common to all the type-bars *a*, and follows the curve of their bearing *e*, so as to normally be in the position to engage the projection *m* on the bushes *d*, as in Fig. 4, when any bar is operated, so as to check the said bar until the check-lever *q* is engaged by the hammer *n*, which pushes it back upon its hinge *r* and with it moves back the check-bar *s* out of engagement with the projection *m*, as shown in Fig. 5. The type-bar is now free and, as before described, is forced onto the printing-surface *k* by the impetus of the hammer *n*, or if already there, as it may be in some cases where the action is very quick, the hammer simply effects the printing or manifolding by striking the type-bar. The lever *q* is forked at *t*, where it is engaged by the hammer *n*, so that the type-bars *a* will pass within the fork and not operate the check.

Although I have described one form of check or check-action, I wish it to be understood that I do not limit myself to the particular form shown, as I may without departing from the nature of my invention employ check or check-actions of various kinds—such, for instance, as a spring or equivalent check adapted to stop the type-carrying part, but to be overcome by the hammer, and also instead of applying the check to the type-bar it may be applied to the key-levers with equivalent effect.

The hammer *n* or the striking-surface on the back of the type-bars *a* may be covered with rubber, felt, cotton, fiber, paper, or any other substance, or an air-cushion may be provided thereat, such covering or cushion (marked *u* on the drawings) serving to deaden or decrease the sound of metallic contact and so produce a practically noiseless type-writer or one in which noise is reduced to a minimum.

In order that springs may be dispensed with and the weight of the type-bars *a*, levers *b*, and hammer *n* utilized after operation to return the parts to their normal position, the said bars are arranged to be normally in su-

perposition, as shown, and at a slight angle to the keyboard.

In the particular type-writer illustrated each type-bar will carry three type, as shown at *v w x*, and suitable means will be employed for adjusting the printing-platen to the particular row of type required.

Having now described my invention, what I claim as new, and desire to secure by Letters Patent, is—

1. In type-writers the combination with the rigid type-carrying parts of a check adapted to check the movement of said type-carrying parts and a hammer for overcoming or releasing said check and forcing the type upon the printing-surface.

2. In type-writers the combination with a series of type-bars of a check-action for checking the type-bars at any desired part of their movement and a hammer operated with the type-bars and adapted to release said check-action and act upon the type-bar to effect the printing of the type.

3. In type-writers the combination with a type-bar of a check-action for checking the said type-bar at any desired point of its movement and a hammer operated with said type-bar and adapted to release the said check-action and act upon the type-bar to effect the printing of the type.

4. In type-writers the combination with a series of key-levers and type-bars of a check for checking the key-levers and type-bars and a hammer for overcoming said check and forcing the type upon the printing-surface.

5. The improvement in type-writers comprising the combination with a series of type-bars and hammers of a check-action comprising a hinged lever with a bifurcated extremity projecting in the line of travel of the type-bars and hammer so as to be free of the former but engaged by the latter, a check-bar on said lever common to all the type-bars and adapted to engage and check same at or before they reach the printing-surface and release the same when engaged by the hammer, substantially as set forth.

6. In a type-writing machine such as described the combination with a series of bars and hammers of a stop upon the bush of the type-bars, a check-bar common to all the type-bars and adapted to temporarily engage said stop, a spring-pressed lever carrying said universal check-bar and hinged to the frame at its lower end and having a bifurcated upper end bent forward into the line of travel of the type-bars and hammers so as to be free of the type-bars but engaged by the hammer, substantially as and for the purposes set forth.

In witness whereof I have hereunto signed my name in the presence of two subscribing witnesses.

WALTER BERESFORD.
